[57] CLAIM

The ornamental design for a support for meat or the like, as shown and described.

DESCRIPTION

FIG. 1 is a front elevational view of a support for meat or the like, showing our new design, the rear view being a mirror image thereof;

FIG. 2 is a side elevational view thereof, the opposite side being a mirror image thereof;

FIG. 3 is a top plan view thereof;

FIG. 4 is a bottom plan view thereof;

FIG. 5 is a front elevational view of a second embodiment of that shown in FIG. 1, the rear view being a mirror image thereof;

FIG. 6 is a side elevational view thereof, the opposite side being a mirror image thereof;

FIG. 7 is a top plan view thereof; and

FIG. 8 is a bottom plan view thereof.

The rear elevational views of the embodiment shown in FIGS. 1 and 5 are mirror images of the front elevational views shown in FIGS. 1 and 5, respectively. The side elevational views of the embodiments shown in FIGS. 2 and 6 are mirror images of the side elevational views shown in FIGS. 2 and 6, respectively.

fig.1.

fig.2.
